CLAIM

The ornamental design for a snowmobile body as shown and described.

DESCRIPTION

FIG. 1 is a perspective view taken from a front, left side of a snowmobile body according to our design;

FIG. 2 is a perspective view taken from a front, right side thereof;

FIG. 3 is a perspective view taken from a rear, left side thereof;

FIG. 4 is a perspective view taken from a rear, right side thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a close-up view of section 11 of FIG. 1;

FIG. 12 is a close-up view of section 12 of FIG. 2;

FIG. 13 is a close-up view of section 13 of FIG. 3;

FIG. 14 is a close-up view of section 14 of FIG. 4;

FIG. 15 is a close-up view of section 15 of FIG. 5;

FIG. 16 is a close-up view of section 16 of FIG. 6;

FIG. 17 is a close-up view of section 17 of FIG. 7;

FIG. 18 is a close-up view of section 18 of FIG. 8;

FIG. 19 is a close-up view of section 19 of FIG. 9; and,

FIG. 20 is a close-up view of section 20 of FIG. 10.

The dot-dash lines in FIGS. 1-20 are provided for annotative purposes only to show the areas of enlargements. The dot-dash lines do not illustrate structures or subject matters and do not form part of the claimed design.

APPLICATION NO. : 29/846085
DATED : April 15, 2025
INVENTOR(S) : Maxime Dumont et al.

Page 1 of 1

It is certified that error appears in the above-identified patent and that said Letters Patent is hereby corrected as shown below:

On the Title Page

DESCRIPTION, "The dot-dash lines in FIGS. 1-20 are provided for annotative purposes only to show the areas of enlargements. The dot-dash lines do not illustrate structures or subject matters and do not form part of the claimed design." should read --Throughout the Figures, where shown: (i) the dashed lines showing portions of the snowmobile form no part of the claimed design; (ii) the dot-dash lines showing portions of the snowmobile in Figures 1, 2, 5, 11, 12, 15, and 20 illustrate boundaries of surfaces claimed as part of the design and form no part of the claimed design; and (iii) the dot-dash boxes in Figures 1 to 20 are provided for annotative purposes only to show the areas of enlargements. The dot-dash boxes do not illustrate structure or subject matters and do not form part of the claimed design.--
